UNITED STATES PATENT OFFICE.

EUGENE C. ROWLEY, OF SEATTLE, WASHINGTON.

CRYSTAL DETECTOR FOR RADIO APPARATUS.

Application filed December 27, 1922. Serial No. 603,292.

To all whom it may concern:

Be it known that I, EUGENE C. ROWLEY, a citizen of the United States, residing at Seattle, in the county of King and State of 5 Washington, have invented certain new and useful Improvements in Crystal Detectors for Radio Apparatus, of which the following is a specification.

My invention relates to a crystal detector for radio apparatus and particularly to an improvement in that part of the detecting apparatus which is known in the art as the "cat's whisker."

The invention has for its particular object to improve this element of crystal detector sets, which in practice is employed to locate the radio active spots or points on the crystal and convey the audio waves to a telephone or other instrument designed to 20 make audio frequency audible to the ear.

In heretofore known devices of this type it has been customary to provide a single wire which is adapted to be moved about the face of the crystal to locate the radio 25 active spots, and in contra-distinction to this, my invention contemplates a detecting device comprising a plurality of wires, the invention being capable of being used with any number of wires whereby a plurality of 30 points on the crystal receiving the audio waves may be engaged by the detecting device and the efficiency of the same manifestly increased.

My invention is capable of adaptation to 35 most of the known commercial types of crystal detectors now on the market and is furthermore so constructed as to enable the same to be varied and modified without the aid of a person particularly skilled in the 40 art to adapt it to the type of crystal detector at hand, and the purpose and duty for which it is to be employed.

The invention will be made more apparent as the description proceeds, especially when 45 considered in connection with the accompanying drawings wherein;

Figure 1 is a side elevation of a crystal detector with my invention applied thereto;

Fig. 2 is a top elevation of the structure 50 illustrated in Fig. 1;

Fig. 3 is an end elevation of the detector;

Fig. 4 is a fragmentary side elevation of the same;

Fig. 5 is a detail perspective view of the same;

Fig. 6 is an end view indicating the manner in which the detecting wires may be multiplied; and,

Fig. 7 is a detail perspective view showing a slight modification of the detector 60 which is capable of attachment to detector sets already in commercial use.

At the outset it should be understood that only so much of a radio receiving set is illustrated as is necessary to show the application of my invention, and that the type of crystal detector set herein described and shown in the drawings is for illustrative purposes only, it being obvious as the description proceeds that the invention is applicable with an equal degree of efficiency to practically all types of crystal detectors.

In the drawings I have shown a crystal detector having a base 10 upon which are supported a pair of posts 11 and 12. A pair of binding posts 13 are provided, electrical connection being established between one of the posts 11 and a binding post 13 by means of an electrical conductor 14, and from the other post 12 to the other of the 70 binding posts 13 by an electrical conductor 15. These electrical conductors, 14 and 15, are preferably disposed in a recess formed on the under side of the base 10, but obviously this structure may be changed to suit the particular designs of the manufacturer.

Secured to one of the posts, and in the illustrated example herein shown, the post 11, is a crystal cup 16, which is adapted to receive the crystal 17, this crystal projecting slightly from the open side of the crystal cup 16, as clearly illustrated in Figs. 1 and 2.

In practice it has been customary to provide a single fine wire movable over the face of the crystal, this wire being known in the art as the "cat's whisker." By my invention I contemplate modifying this arrangement and to provide instead a plurality of wires which may be caused to engage the face of the crystal to search out or locate the radio active spots or points. In constructing my

improved type of detecting apparatus I provide a disc 18 apertured centrally thereof for the reception of a rod 19, the rod 19 having a head 20' which engages the disc 18. The disc 18 is formed with a plurality of notches or recesses 20 arranged around its periphery and a plurality of apertures 21 arranged in a circumferential row adjacent the periphery of the disc.

10 In practice I contemplate employing a plurality of U-shaped wires 22, which are passed through the apertures 21 of the disc 18 and project from one face of the disc at right angles to the plane of the same. The 15 number of these U-shaped wires may be varied according to the type of detector set employed, and the purpose of the operator, it being possible to provide, for instance, eight points, as illustrated in Fig. 5, or sixteen points, as illustrated in Fig. 3. It 20 is also possible to mount sufficient of the U-shaped wires upon the disc 18 so as to provide thirty-two points, as suggested in Fig. 6. In the first instance four of the U-shaped 25 wires will be mounted upon the disc, these wires being inserted through pairs of the apertures 21.

In Fig. 3 eight of the U-shaped wires are 30 illustrated, these U-shaped wires having one leg passing through the apertures 21, while the other leg passes through the notches 20 arranged around the periphery of the disc. In this instance sixteen detecting points are 35 provided.

As suggested in Fig. 6 thirty-two detecting 40 points may be provided by inserting the U-shaped wires with the adjacent legs of the U-shaped wires through the same slot, and by further mounting a set of U-shaped wires with one leg thereof extending through the 45 apertures 21 and the other leg extending through the notches 20.

Obviously, any number of points under 45 may be provided by varying the number of U-shaped wires mounted upon the disc 18.

After the wires have been mounted upon the disc in a number sufficient to provide the 50 number of wire points required, there is slipped upon the shaft 19 an apertured disc 23 which will herein be termed the binding disc. The shaft 19 adjacent its head 20' is externally threaded to receive a clamping nut 24 whereby the disc 23 may be pressed 55 against the bases of the U-shaped wires to firmly clamp the same in place.

In practice it is customary to interpose a 60 spring 25 between the nut 24 and the supporting post 12 upon which the shaft 19 is mounted, and to provide on the end of the shaft 19 a handle 26. It is also customary to so mount the shaft 19 that the end carrying the wires which engage the crystal is capable of a swinging or swivelled movement

whereby the wires may be caused to engage 65 the entire exposed surface of the crystal 17.

While from the description of my invention noted hereinbefore it has been explained how it is possible to mount a sufficient number of wires onto the plate 18 so as to provide thirty-two points, still in practice it has been found that from eight to sixteen points are most efficient, as too many points present too solid a surface to the crystal and thus the best results are not obtained. Obviously the spring will hold the detector wires into engagement with the crystal surface, and by providing a multiplicity of detecting points the radio active point may be found with considerable greater ease and in less time, and furthermore the connection will not be affected by slight jarring.

In Fig. 7 I have shown a slightly modified form of construction, the only difference being that in place of the shaft 19 I have provided a stub shaft 27, a clip 28 being clamped preferably between the nut 24 and the clamping disc 23, and an operating rod 29 being fixed to the clip 28 for operating the detector head. In this manner a detector head constructed in accordance with my invention and provided with a multiplicity of wires may be connected to the handle which carries in commercially known sets the single "cat's whisker."

Obviously the size of the wires 22 may be varied and after they have been clamped onto the disc 18 the ends thereof may be cut so that the wires will project from this disc the desired length. Also it is possible to spread the wires, inasmuch as they are easily bendable, thus presenting to the crystal a detecting head of the size and shape desired.

Obviously, with a detector constructed in accordance with my invention a more durable structure is obtained, inasmuch as the necessity for loose connections or coiled wires or the like is eliminated. By presenting to the crystal a larger surface composed of a plurality of wires, the spring 25 may be of such strength as to hold the detector head against the crystal against displacement by ordinary jars. Furthermore it has been found that inasmuch as it is not necessary to see the crystal in order to find its radio active points a detector constructed in accordance with my invention may be enclosed in a tube or a cabinet, leaving exposed only the handle for adjusting the head.

From the foregoing it will be apparent that I have provided a simple, compact and efficient detector for use in all types of crystal detector sets for radio apparatus and while certain illustrative examples have been employed in describing my invention it should be understood that I do not wish to

be unnecessarily limited as to details of construction but reserve the right to make such changes as may come within the purview of the accompanying claims.

5 Having thus described my invention what I claim is:

1. A multi-point contact element for a crystal detector comprising a conducting disk, a clamping disk, means for securing 10 said disks together, and a plurality of cat whiskers secured between said disks.

2. A crystal detector element comprising a conducting disk, a clamping disk and means for securing the same to said first 15 named disk, and a plurality of wires mounted between said disks to provide a plurality of contact points.

3. A crystal detector element comprising a conducting disk, a clamping disk and 20 means for securing the same to said first named disk, a plurality of wires mounted between said disks to provide a plurality of contact points, and means for mounting said detector element adjacent the crystal.

25 4. A detector for use in combination with radio crystal detector sets comprising a disc provided with a plurality of apertures and peripheral notches, a plurality of wires adapted to be removably mounted on said

disc by extending through said apertures 30 and notches and means for clamping said wires to said disc.

5. A detector for use in combination with radio crystal detector sets comprising a disc provided with a plurality of apertures and 35 peripheral notches, a plurality of U-shaped wires adapted to be removably mounted on said disc and to extend through said apertures and notches, a headed shaft passing axially through said disc, a clamping disc 40 on said shaft for holding said U-shaped wires in place and a binding nut engaging said clamping disc.

6. In a radio crystal detector set a detector 45 comprising a disc provided with a plurality of apertures and peripheral notches, a plurality of U-shaped wires adapted to extend through said apertures and notches and to project from one face of said disc, a shaft 50 for said disc, a clamping disc engaging said wires, a binding nut on said shaft, means for mounting said shaft so as to position said detector adjacent said crystal and spring means for holding said detector in engagement with said crystal. 55

In testimony whereof I affix my signature.

EUGENE C. ROWLEY.
